(57) **CLAIM**

The ornamental design for an outer container of packaging box for storage, as shown and described.

DESCRIPTION

FIG. 1 is a bottom rear perspective view of an outer container of packaging box for storage showing my new design;

FIG. 2 is a front view thereof;

FIG. 3 is a rear view thereof;

FIG. 4 is a right side view thereof and the left side view being a mirror image;

FIG. 5 is a top view thereof;

FIG. 6 is a bottom view thereof;

FIG. 7 is a reference view, showing an enlarged cross-sectional view taken along the line 7-7 in FIG. 5;

FIG. 8 is an enlarged view of portion 8 shown in FIG. 1;

FIG. 9 is an enlarged view of portion 9 shown in FIG. 1;

FIG. 10 is an enlarged view of portion 10 shown in FIG. 1; and,

FIG. 11 is an enlarged view of portion 11 shown in FIG. 1. The dashed broken lines in the figures show portions of the packaging box for storage that form no part of the claimed design. The dot-dash broken lines depict the boundaries of the enlargements and form no part of the claimed design.

1 Claim, 10 Drawing Sheets
